CLAIM

The ornamental design for a table tennis net, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a table tennis net, embodying my new design according to a first embodiment;

FIG. 2 is a front view thereof set up on a table tennis table;

FIG. 3 is another perspective view thereof;

FIG. 4 is a partial top perspective view thereof;

FIG. 5 is a perspective view of a table tennis net, embodying my new design according to a second embodiment; and

FIG. 6 is a front view thereof set up on a table tennis table; FIG. 7 is another perspective view thereof;

FIG. 8 is a partial top perspective view thereof; and,

FIG. 9 is a partial top plan view thereof.
